WINDING MACHINE

John V. Keith, Warwick, R. I., assignor to Universal Winding Co., Cranston, R. I., a corporation of Massachusetts

Application May 4, 1951, Serial No. 224,491

14 Claims. (Cl. 242—18)

The present invention relates to winding machines and more particularly relates to a high speed winding machine of the "precision winding" type.

In the following specification and claims the term "yarn" is employed in a general sense to apply to all kinds of strand materials, either textile or otherwise, and the designation "package" is intended to mean the product of the machine whatever its form.

One object of the present invention is to provide a high speed precision winding machine.

Another object of the present invention is to provide a winding machine capable of operating at maximum speed throughout the winding cycle.

Another object of the present invention is to provide a winding machine wherein the speed of operation of the machine is controlled by the maximum operating speed of its traversing means, during the first part of a winding cycle, and the speed of operation is controlled by the strength of the yarn being wound during the latter part of the winding cycle.

Another object of the present invention is to provide a winding machine adapted to operate at a substantially constant spindle speed during the first part of the winding cycle and to operate at a substantially constant yarn speed during the latter part of the winding cycle.

Another object of the present invention is to provide a winding machine having a substantially fixed thread line throughout the winding cycle.

Another object of the present invention is to provide a winding machine having a reciprocating yarn guide and wherein said yarn guide is self-threading and of very small mass.

Another object of the present invention is to provide a winding machine wherein the reciprocating yarn guide is mounted to reduce vibration to a minimum.

Another object of the present invention is to provide a winding machine wherein the package of yarn being wound is positively moved away from the yarn guide as the package increases in size.

Another object of the present invention is to provide a winding machine having means for positively controlling the pressure with which the yarn being wound is applied to the package.

Another object of the present invention is to provide a winding machine capable of winding yarn with controlled tension and pressure.

Another object of the present invention is to provide a winding machine having automatically resettable means for controlling the pressure with which the yarn being wound is applied to the package.

Another object of the present invention is to provide a winding machine having a clutch member adapted to connect and disconnect the winding spindle to a source of power and which is energized by said source of power.

Another object of the present invention is to provide a self-cleaning yarn tensioning mechanism.

Another object of the present invention is to provide a yarn tensioning mechanism having a movable element

2

adapted to discharge accumulations of foreign matter therefrom.

Another object of the present invention is to provide a yarn tensioning mechanism having a rotating element adapted to discharge foreign matter therefrom.

Another object of the present invention is to provide a winding machine having a self-cleaning yarn tensioning mechanism driven by said winding machine.

Another object of the present invention is to provide a winding machine adapted to actuate a self-cleaning yarn tensioning mechanism.

Other objects of the invention will in part be obvious and will in part appear hereinafter.

The invention accordingly comprises the apparatus 15 possessing the construction, combination of elements and arrangement of parts which are exemplified in the following detailed disclosure, and the scope of the application of which will be indicated in the claims.

For a fuller understanding of the nature and objects of the invention, reference should be had to the following detailed description taken in connection with the accompanying drawings wherein:

Fig. 13 is a side elevation of the tension means and showing the tension means in its inoperative position;

Fig. 14 is a view similar to Fig. 11 but showing the tension means in operative position; and

Fig. 15 is a view of the other side of the tension mechanism and showing said mechanism in operative position.

General description.—The present invention comprises a winding machine for winding yarn with a universal, precision or V-wind. In the usual type of machines for winding yarn with a universal, precision or V-wind the winding spindle is driven positively at a constant rate of speed to rotate the package and the yarn is traversed lengthwise of the spindle with the rate of draft of the yarn increasing progressively as the package increases in diameter. In this type of winding machine the traversing thread-guide is reciprocated at a uniform rate, that is, in certain ratio to the speed of the winding spindle except

for a slight increase therein to give an increment of motion to the guide whereby it will lay the yarn in helical coils with each coil in closely adjacent relation to the previously wound coil. With this type of precision winding the package is built up with the turns or coils in all of the layers extending from end to end of the package in a predetermined number of convolutions and crossing

each other with a symmetrical V-shaped pattern on the surface of the package.

The maximum speed at which yarn can be wound by any winding machine is limited by the speed at which it can be delivered by the supply package from which the yarn is being wound. Attempts to wind in excess of the speed at which the yarn is freely delivered results in damaged yarn and a large number of broken ends. In the usual type of precision winding machine the speed of rotation of the winding spindle is limited to a speed which will not impart a lineal speed to the yarn being wound, at the completion of the winding cycle when the package of yarn is at its maximum diameter, which is in excess of the lineal speed at which the yarn can be safely delivered from the yarn supply. As a result, the usual type of precision winding machine operates during practically all of its winding cycle at a rate slower than the maximum speed possible. For example, if the machine is winding yarn from cakes capable of delivering the yarn at a speed of approximately six hundred yards per minute, the winding spindle would be set to rotate at a speed which would wind the yarn at approximately six hundred yards per minute when the package being wound reaches its maximum diameter. If the package being wound is to be six inches in diameter when it is finished this means that the winding spindle will wind the yarn at the start of the package at about two hundred yards per minute.

The present invention comprises a winding machine for winding precision wound packages of yarn at the highest possible winding speed. The winding machine of the present invention includes a plurality of similar winding units driven by a common source of power, each winding unit being capable of winding independently of the others to wind a precision wound package. Each winding unit includes a rotatable spindle adapted to receive and hold a yarn receiving member or core, and a rotatable cam adapted to reciprocate a yarn guide longitudinally of the yarn receiving member or core a predetermined number of times for each revolution of the winding spindle.

When the winding cycle of a precision winding machine starts, the speed at which the winding spindle can be rotated is definitely limited by the speed that the cam can be rotated. This is due to the eccentric shape of the cam and the uneven loading placed thereon by the rapid reversal of the mass of the yarn guide which it must reciprocate back and forth thereby definitely limiting the speed at which it is safe and practical to rotate the cam. As the winding cycle progresses and the package of yarn being wound increases in diameter, the lineal speed of the yarn being wound increases due to the increase in package diameter. At some point in the winding cycle the maximum speed at which the yarn can be wound, due to the above mentioned limitations on the speed at which the yarn can be delivered by the yarn supply, will be attained and if the winding speed increases thereafter, the yarn will break or be damaged. Therefore the winding machine of the present invention is so constructed that the start of the winding cycle, its speed is the maximum speed at which the yarn traversing cam can operate, and when the package of yarn being wound attains such a size that the yarn is being wound at its maximum practical yarn speed, the speed of rotation of the winding spindle and the yarn traversing cam is reduced at a predetermined rate to maintain a substantially constant yarn speed.

The yarn traversing mechanism of the winding machine embodying the present invention is fixed with respect to the axis of the winding spindle. That is, the yarn guide does not swing or move away from the axis of the package being wound as said package increases in diameter but reciprocates along a fixed line throughout the winding operation. However, the winding spindle is arranged to move away from the yarn traversing mech-

anism as the package being wound grows. Moving the package away from the yarn guide accomplishes three distinct advantages in the present invention. First, it permits the yarn traversing mechanism, which includes a rapidly reciprocating yarn guide, to be firmly mounted on the apparatus to minimize vibration from the reciprocating parts. Second, it permits a substantially straight thread line from the supply of yarn being wound to the winding spindle and permits maintaining that substantially straight thread line without change throughout the winding cycle. Third, inasmuch as the yarn being wound contacts the yarn guide at the same point and same angle throughout the winding cycle it is possible to employ a self-threading yarn guide having a small mass thereby permitting higher cam speeds than would be possible if the guide had to be large enough to catch the yarn throughout the range of a changing yarn angle.

A mechanism is provided which is driven by the winding spindle and which is adapted to positively move the winding spindle away from the yarn guide as the package increases in diameter at a rate substantially equal to the growth of the package to maintain the surface of the package being wound just out of contact with the yarn guide, or to permit the yarn guide to exert only a predetermined pressure against the package.

The winding machine of the present invention is provided with a magnetic type tension capable of automatic adjustment by the apparatus as the package being wound increases in diameter to provide a differential tension, i. e. a constantly decreasing tension from the start of the winding cycle to its end. The tension mechanism is provided with a self-cleaning pressure plate in the form of a rotatable disc having a plurality of grooves formed in its face. The disc is constantly rotated at a uniform rate of speed whereby foreign matter carried into the tension applying portion of the mechanism by the yarn are collected in the grooves and carried out of the tension applying portion and discharged before they can accumulate to an extent sufficient to interfere with the function of the tension.

Winding units.—The apparatus of the present invention comprises a plurality of winding units 10 adapted to be mounted on a bed formed from two parallel horizontal bars 12 supported by legs 14. The apparatus may be double-sided, i. e. have a plurality of winding units on both sides of the bed or table, or can be single-sided as illustrated in Figure 1. All of the winding units on a side are driven by a single motor 16. In the event the apparatus is double-sided two motors would be employed, one operating all of the winding units on one side and the second to operate all of the winding units on the other side. A shelf 15 extends longitudinally of the apparatus supported by legs 14 and serves as a support for the supplies of yarn to be wound by the winding units.

Inasmuch as all of the winding units on the winding machine of the present invention are similar, only one such unit will be explained in detail. Each winding unit comprises a rotatable spindle adapted to receive a package core or yarn holder 18 and a traverse mechanism 20 adapted to traverse a strand of yarn longitudinally of the core 18 to wind a package of yarn thereon.

Traverse mechanism 20, Figs. 1, 2, and 3, is carried by a bracket 22 which is secured to the front rail 12 of the bed or table in such a manner that said traverse mechanism projects forwardly therefrom. The traverse mechanism 20 comprises a housing 24 secured to bracket 22 by any convenient means which will permit it to be pivoted slightly thereon to make it possible to adjust said traverse mechanism so that it will reciprocate its yarn guide 28 parallel to the surface of package cores 18 having different tapers. Housing 24 is provided at its front and back ends with journals which serve as bearings for a shaft 26. Shaft 26 carries a multi-grooved barrel cam, not shown, within said housing 24 and which is connected to and drives yarn guide 28 in a manner well known to those

skilled in the art. Shaft 26 projects from the back of housing 24 and has fixedly secured thereon a toothed pulley 30, Figs. 2, 5 and 6, which is driven by a cogged belt 32, in a manner to be explained more in detail hereinafter, to rotate shaft 26 and the barrel cam carried thereby to reciprocate yarn guide 28 longitudinally of package core 18.

The winding spindle comprises a horizontal shaft 34 rotatably journaled by means of suitable bearings in the front and back walls 33 and 35 respectively of housing 36 and adjacent the upper end of housing 36. Housing 36 also has a side wall 37. Housing 36 is mounted for pivotal movement on shaft 38, which is fixedly attached to horizontal bars 12, by means of suitable bearings located in the lower ends of walls 33 and 35 to permit shaft 34 and housing 36 to swing towards and away from traverse mechanism 20 about shaft 38 as an axis. A toothed pulley 40 is fixedly mounted on shaft 34. A pair of toothed pulleys 42 and 44 are rotatably carried on shaft 38 by means of a clutch mechanism 45, to be explained in detail hereinafter. Pulley 42 is in alignment with pulley 40 and drivingly connected thereto by means of a cogged belt 46. Pulley 44 is in alignment with one side of a double toothed pulley 48, rotatably carried by stub shaft 50 which is secured to bed or table 12, and is drivingly connected thereto by means of cogged belt 52. The other side of double pulley 48 is in alignment with pulley 30 on shaft 26 and is connected thereto by cogged belt 32 to rotate said shaft 26 and the barrel cam carried thereby.

It will therefore be seen that when clutch mechanism 45 is engaged, to be more fully explained hereinafter, to rotate pulleys 42 and 44 that shaft 34 will be rotated by means of pulleys 40 and 42 and belt 46 to cause yarn to be wound on package core 18, and that yarn guide 28 will be reciprocated adjacent core 18 by reason of pulleys 44, 48 and 30, and belts 52 and 32 rotating shaft 26 and the barrel cam carried thereby.

As stated above pulleys 42 and 44 are rotatably carried on shaft 38 by means of a clutch mechanism 45. Clutch mechanism 45, Figs. 5, 8, 9 and 10, comprises a sleeve 54 rotatably journaled on shaft 38. Pulleys 42 and 44 are keyed to sleeve 54 adjacent its right hand end for rotation around shaft 38 with said sleeve. A V-pulley 56 is journaled on sleeve 54 for rotation thereon adjacent to pulley 42 and has a clutch facing 58 of any convenient material affixed to its left hand side so that the left side of pulley 56 is adapted to function as a clutch plate. A cooperating clutch plate 60 is carried on sleeve 54 for limited rotational and axial movement thereon by means of a hub member 62. Hub member 62 is provided on its end with an annular groove 64 which divides said hub into an outer flange 66 and an inner flange 68. Inner flange 68 is provided with a helical slot 70 which receives radial pin 72 projecting from the surface of sleeve 54. It will be seen therefore that rotation of clutch plate 60 and hub 62 relative to sleeve 54 will cause radial pin 72 to cam clutch plate 60 towards or away from pulley 56 and its clutch facing 58. A helical spring 74 having one of its ends attached to radial pin 72 and its other end engaged in a hole in the base of annular groove 64 tends to rotate clutch plate 60 and hub member 62 in a direction to cause radial pin 72 to cam said clutch plate against the clutch facing 58 of pulley 56. A brake 76 operated by starting handle 80, to be explained more in detail hereinafter, is located around outer flange 66 of hub member 62.

Upon the operation of starting handle 80 in a direction to stop the operation of the winding unit, brake 76 is caused to engage said outer flange 66 to stop the rotation of hub 62 and clutch plate 60. Stopping, or applying a braking effect to hub member 62 causes sleeve 54, due to its inertia, to rotate relative to hub 62 and cam said hub and clutch plate 60 away from the V-pulley 56 and its clutch facing 58 to permit pulley 56 to rotate freely on sleeve 54. When starting handle 80 is moved

in a direction to start the winding unit, brake 76 is released permitting helical spring 74 to rotate hub member 62 in a direction to cause radial pin 72 to cam said hub and clutch plate 60 against clutch facing 58 of pulley 56. Once clutch plate 60 and clutch facing 58 engage the rotation of clutch plate 60 imparted thereto by the pulley 56 causes cam slot 70 to cam said clutch plate tightly against clutch facing 58.

Starting and stopping mechanism.—A starting lever 80 is pivotally mounted on the right hand end of bracket 22, Figs. 3 through 7, by means of a hinge member 82 to which it is fixedly attached. An L-shaped actuating arm 84 is attached at one of its ends to hinge member 82 with its other end adjacent one end of brake member 76. The free end of L-shaped actuating arm 84 is attached to the adjacent end of brake member 76 by means of a compression spring 86 and rod 88 connection, and the other end of brake 76 is fixedly attached to the rear bar 12 of bed or table so that downward movement of starting handle 80 swings L-shaped actuating arm 84 to release brake 76 from outer flange 66 of the clutch mechanism 45 to permit said clutch to engage and start the winding mechanism operating. Upward movement of the starting handle 80 swings L-shaped actuating arm 84 in a direction to draw brake 76 tightly against the outer flange 66 of clutch mechanism 45 to disengage said clutch all in the above described manner.

Starting handle 80 is provided adjacent hinge member 82 with an upstanding finger 90, Figs. 3, 4 and 7, which is pivotally connected at its upper end to one end of a link 92, the other end of link 92 is pivotally connected to bracket 22 so that link 92 and upstanding finger 90 form a toggle that straightens as starting handle 80 is depressed to start the winding unit and which folds when said handle moves upward to stop the winding mechanism. A roller 94 is provided between the ends of link member 92 and is adapted to be engaged by a spindle moving cam, to be explained in detail hereinafter, to permit said cam to move the winding spindle away from yarn guide 28 as the package being wound increases in diameter. A pin 91, located on a boss 93 on bracket 22, serves as a stop for link 92 to limit the downward movement of starting handle 80 to thereby insure roller 94 being located in the proper position for the successful operation of the spindle moving cam. Starting handle 80 is spring urged in an upward or clockwise direction, as viewed in Figs. 3, 4 and 7, by means of a helical spring 96 carried by the pivot pin of hinge member 82.

A latch member 98, Figs. 3 and 4, is pivotally mounted intermediate its ends on the lower edge of bracket 22 by means of a stud 100 and is spring urged to rotate in a counterclockwise direction by means of a spring 102. The upper end of latch member 98 is bent over to form a latch shoulder 104 adapted to engage over a keeper member 106 formed on the back side of starting handle 80 by the head of stud 108. Latch shoulder 104 is of sufficient length so that keeper member 106 bears against its surface when starting handle 80 is in its uppermost position as illustrated in Fig. 4. When starting handle 80 is depressed to cause clutch mechanism 45 to engage to start the winding unit, keeper 106 slides downwardly along the face of latch shoulder 104 until link 92 engages pin 91 at which time keeper member 106 passes below latch shoulder 104 and spring 102 rotates latch member 98 to move said shoulder 104 over said keeper member to thereby hold starting lever 80 in the operating position.

Means are provided for automatically releasing latch shoulder 104 from keeper member 106 upon the breaking or exhaustion of the yarn being wound. The releasing means comprises an inverted Y-shaped lever 110 pivoted intermediate its ends by means of stud 112 to latch member 98 in such a manner that upward movement of said Y-shaped lever 110 will rotate said latch member 98 in a clockwise direction to move latch shoulder 104 off from keeper member 106. The upper arm 114 of Y-shaped le-

ver 110 is provided with an elongated slot 116 which fits loosely over stud 108 to permit limited pivotal movement of said Y-shaped lever in a manner to be described hereinafter. The uppermost end of upper arm 114 is provided with an arcuate slot 118 adapted to adjustably hold a balancing weight 120. The lower right hand arm 122 of Y-shaped lever 110 is provided with a forwardly extending yarn engaging bar 124 adapted to engage the strand of yard Y being wound on package core 18 to permit said strand of yarn to hold said Y-shaped lever against clockwise rotation. The lower left hand arm 126 of Y-shaped lever 110 is provided at its end with an abutment 128 formed by bending over the end of said arm. Abutment 128 is adapted to pass under one of the teeth on toothed wheel 130, carried by shaft 132, upon the breakage or exhaustion of the strand of yarn Y which permits Y-shaped lever 110 to pivot in a clockwise direction within the limits of slot 116. Toothed wheel 130 is rotated by shaft 132 in a clockwise direction as viewed from the left of Fig. 3 or Fig. 4, i. e. the front of wheel 130 is moved downwardly and the back upwardly. The lower left hand arm 126 of lever 110 is located in back of shaft 132; therefore when abutment 128 is engaged by one of the teeth on toothed wheel 130 rotation of said wheel lifts lever 110 to thereby rotate latch member 98 in a clockwise direction to release latch shoulder 104 from keeper member 106. Immediately upon the release of keeper 106 from latch shoulder 104 starting handle 80 swings upwardly under the influence of its spring 96 causing stud 108 to move upwardly in elongated slot 116. Elongated slot 116 is so shaped that the upward movement of stud 108 therein swings lever 110 a small amount in a counterclockwise direction to disengage abutment 128 from toothed wheel 130 and to hold said abutment thus disengaged.

A depending arm 134 forming a part of a tension control mechanism and a speed regulating mechanism, to be explained in detail hereinafter, is adjustably mounted on the front of housing 36 adjacent shaft 38. The lower end of depending arm 134 is bent over to form a lug 136 which is adapted to engage the lowermost end 138 of latch member 98 to disengage latch shoulder 104 from keeper member 106 when the package being wound has reached its predetermined desired size.

Pressure control mechanism.—Each winding unit is provided with a pressure control mechanism adapted to move the winding spindle and the package being wound thereon away from yarn guide 28 at a rate substantially equal to the rate at which the yarn builds up on the package to prevent the yarn from being applied to the package at an excessive pressure and to thereby prevent yarn damage and distortion of said package. The pressure control mechanism comprises a spiral cam 140 carried by housing 36 which is rotated through a predetermined angle of arc for each revolution that the winding spindle makes and which has its periphery in engagement with roller 94 carried by link 92. Spiral cam 140 is rotated by horizontal shaft or spindle 34 by means of a speed reducing system comprising a worm gear 142, Fig. 5, on shaft 34 which meshes with and drives worm wheel 144 fixedly attached to shaft 146. Shaft 146 is suitably journaled in side wall 37 of housing 36 and projects therethrough to the outer surface thereof. A crank disk 148 is fixedly secured to the outer end of shaft 146 and is provided with a plurality of threaded holes 150 each spaced a different radial distance from the axis of said disk adapted to selectively receive a crank pin. A crank pin 152 is threadedly carried by one of the holes 150 and has connected thereto one end of a connecting rod 154. The other end of connecting rod 154 is pivotally connected to the tail end of a ratchet pawl 156. Ratchet pawl 156 is pivotally carried by arm 158 which is carried for swinging motion by stub shaft 160 fixedly carried by side wall 37 of housing 36. A ratchet wheel 162 is mounted for rotation on stub shaft 160 and is superimposed on arm 158 to permit ratchet

pawl 156 to engage its teeth. A pinion gear 164 is also carried by stub shaft 160 and is connected to ratchet wheel 162 so that rotation of said ratchet wheel rotates pinion gear 164. A U-shaped friction leaf spring 166 having its solid end attached to side wall 37 contacts the side of ratchet wheel 162 on each side of stub shaft 160 with its other end to apply a frictional drag or braking effect to said ratchet wheel to prevent the ratchet wheel moving with pawl 156 and arm 158 as they rock backwardly preparatory to said pawl engaging a different tooth on the ratchet wheel. Pinion gear 164 meshes with and drives gear 168 of a set of speed change gears comprising gears 168, 170, 172 and 174. Gears 168 and 170 rotate together on stub shaft 176 carried by a movable arm 178 adjustably mounted on side wall 37. Gears 172 and 174 rotate together on stub shaft 180 also carried by movable arm 178. Gear 172 is in mesh with and is driven by gear 170. Gear 174 is in mesh with and drives gear 182. Gear 182 is fixedly attached to the end of shaft 184 which is journaled in side wall 37 of housing 36 and passes therethrough. The inner end of shaft 184 carries worm gear 186. Worm gear 186 is in mesh with and drives worm wheel 188 which is fixedly carried by hollow shaft 190. Hollow shaft 190 passes through the front wall 33 of housing 36 and is rotatably journaled in the boss 192 formed thereon. A ratchet wheel 194 is fixedly attached to the forward end of hollow shaft 190 for rotation thereby. Spiral cam 140 is carried on hollow shaft 190 adjacent ratchet 194 and between it and boss 192 by means of bushing 196 for selective rotation on or with said shaft 190. Cam 140 and ratchet wheel 194 are located adjacent each other and cam 140 is provided with a pawl 198 pivotally mounted thereon by pin 199 and resiliently urged by means of leaf spring 200, also carried by cam 140, into engagement with the ratchet teeth on ratchet wheel 194 so that rotation of ratchet wheel 194 acting through pawl 198 will rotate cam 140. Inasmuch as the periphery of spiral cam 140 bears against roller 94 rotation of said cam in a counterclockwise direction pivots housing 36 and the winding spindle 34 away from yarn guide 28. By the proper selection of change gear 182 and the proper location of crank pin 152 on crank disk 148 the counterclockwise rotation of cam 140 can be adjusted to such a rate that it will move the winding package away from yarn guide 28 at substantially the same rate that the radius of the package increases. The pressure control mechanism is readily adjustable to conform to the winding of different diameter yarns by changing the position of crank pin 152 and employing a suitable change gear 182.

Ratchet releasing means are provided to permit spiral cam 140 to rotate on hollow shaft 190 in a clockwise direction back to its starting position to bring winding spindle 34 closely adjacent yarn guide 28 to permit the start of a new winding cycle. The cam resetting means comprises a pawl releasing link 202 having a rectangular shaped slot 204 formed in its upper end and a smaller oval slot 206 in its lower end. A threaded rod 208 having a cam surface 210 formed on one end thereof passes through slot 204 in the upper end of latch 202 and extends through hollow shaft 190 to hold said link 202 adjacent the outer face of ratchet wheel 194 for limited radial movement by cam surface 210. Slot 206 in the lower end of link 202 fits over pin 199 which holds pawl 198 on cam 140 to cause link 202 to rotate with cam 140 and adjacent said pawl. The lower end of link 202 is provided with an inwardly turned finger 212 which is adapted to extend across the upper surface of pawl 198. It will, therefore, be seen that inward movement of threaded rod 208 causes cam surface 210 formed thereon to react with slot 204 in link 202 to move said link radially outwardly. This outward radial movement of link 202 brings finger 212 thereon against the upper surface of pawl 198 to pivot said pawl outwardly against leaf spring 200 to release said pawl from the teeth of

ratchet wheel 194. A helical spring 214 coiled about boss 192 on housing 36 and having one of its ends hooked around the edge of front wall 33 of said housing 36 and its other end engaging a stud 216 on cam 140 returns said cam to its starting position. An adjustable cam stop member 218 is also carried by bushing 196 for limited pivotal movement thereon. Stop member 218 comprises an arm having an opening 220 formed in one end adapted to fit over bushing 196 and having a bent over portion 222 formed on its other end to provide an abutment adapted to be engaged by arm 224, Figs. 3, 4 and 5, adjustably carried by housing 36 in a manner to be explained hereinafter, to stop cam 140 in a predetermined position with respect to housing 36. A lug 226 is provided on the back surface of cam 140 adapted to engage in a notch 228 in the edge of stop member 218 to stop said cam 140 when it has been returned to its starting position.

Shaft or spindle 34 is provided on its forward end with an expanding mandrel 229 adapted to releasably grip package core 18. A clamping lever 230 is pivotally mounted at the upper forward end of housing 36 and adapted to cause said mandrel 229 to clamp or release said core 18 in a manner well known to those skilled in the art, i. e. pivoting the upper end of lever 230 rearwardly causes the lower end of the lever to swing in a forward direction whereby detent 232 formed thereon reacts against flanged collar 234 to move said collar forwardly to release package core 18. Pivoting handle 230 forwardly causes detent 232 to move flange collar 234 rearwardly to clamp the package core in position. One end of a link 236, Fig. 5, is connected by means of a pin and slot connection to clamping lever 230 above the pivot point of said lever. The other end of link 236 is pivotally connected to the upper end of rod operating lever 238 which projects upwardly through a slot formed in the top of housing 36. Rod operating lever 238 is pivoted intermediate its ends on a stud 240 located inside of the upper end of housing 36. The lower end of rod operating lever 238 is connected to the threaded end of rod 208 by means of a pair of nuts 242. It will, therefore, be seen that forward pivotal movement of clamping lever 230 will pull link 236 in a forward direction thereby pivoting rod operating lever 238 in a direction to draw rod 208 into hollow shaft 190. Inward movement of rod 208 causes cam surface 210 formed thereon to force link 202 radially outward to thereby release pawl 198 from the teeth of ratchet wheel 194 to permit the return of cam 140 to its starting position. It will also be noted that the forward swinging movement of clamping lever 230 actuates expanding mandrel 229 to grip a fresh package core 18. Therefore the act of clamping a fresh package core on mandrel 229 automatically returns cam 140 to its starting position. A helical spring 244 is coiled around stud 240 and has one of its ends engaged in an opening formed in housing 36 and its other end caught around the edge of rod operating lever 238 and functions upon the release of clamping lever 230 to pivot rod operating lever 238 in a counterclockwise direction, as viewed in Fig. 5, to move cam 210 out of engagement with link 202 to permit pawl 198 to again engage the teeth on ratchet wheel 194. This movement of lever 238 and rod 208 is permitted by the pin and slot connection of link 236 to clamp lever 230.

The pressure control mechanism functions in the following manner. Rotation of shaft or spindle 34 to wind yarn Y on package core or yarn holder 18 rotates worm gear 142 which in turn rotates worm wheel 144 and shaft 146. Shaft 146 rotates crank disk 148 to oscillate ratchet pawl 156 back and forth by means of connecting rod 154 and crank pin 152. The amount of oscillation of ratchet pawl 156 can be controlled by the proper selection of the threaded hole 150 in which crank pin 152 is located. Oscillation of ratchet pawl 156 incrementally rotates ratchet wheel 162 in a clockwise direction as viewed in Fig. 11. Rotation of ratchet wheel 162 rotates

pinion gear 164 which is meshed with and drives gear 168. Gear 168 carries and rotates gear 170 which is meshed with and drives gear 172. Gear 172 carries and rotates gear 174. Gear 174 in turn rotates gear 182 and with it shaft 184 and worm gear 186 carried thereby. Worm gear 186 is meshed with and rotates worm wheel 188 fixedly carried by hollow shaft 190. Rotation of hollow shaft 190 rotates ratchet wheel 194 carried thereby and rotation of ratchet wheel 194 acting through pawl 198 rotates spiral cam 140 to cause said cam to react against roller 94 to lift spindle 34 away from thread guide 23. Upon completion of the package being wound and the placing of a new package core 18 upon spindle 34 the operation of clamping lever 230 to lock the new core on the spindle draws threaded rod 208 back into hollow shaft 190 causing cam surface 210 formed on said rod to move pawl releasing link 202 radially outwardly to release pawl 198 from ratchet wheel 194. Upon the release of pawl 198 from the teeth of ratchet wheel 194 spring 214 rotates spiral cam 140 back to its starting position at which point cam stop member 218 engages adjustable cam arm 224 to stop said spiral cam.

Speed and tension control mechanism.—As stated above two factors limit the speed at which a package of yarn can be wound. At the start of the winding cycle the speed at which the yarn guide traversing cam can be rotated determines the maximum speed at which winding can take place. As the package being wound increases in diameter its peripheral speed increases until a peripheral speed is obtained which is equal to the maximum speed at which the strand of yarn being wound can be delivered by the yarn supply without incurring damage to the yarn. The apparatus of the present invention includes a speed controlling means which permits the apparatus to operate at the maximum speed at which its yarn guide traversing cam can safely operate until such time as the package being wound attains a peripheral speed substantially equal to the maximum speed at which the yarn can be wound. When this condition is arrived at a speed control mechanism starts to operate to reduce the speed of rotation of shaft or spindle 34 at such a rate that the peripheral or surface speed of the package being wound will remain constant. This arrangement permits the winding machine of the present invention to operate at the highest possible speed at all times. A motor 16 carried by a bracket 246 attached to legs 14 drives all of the winding units on one side of the winding machine.

Motor 16 drives belt 248, Fig. 1, which in turn drives a plurality of pulleys 250 which are located one under each winding unit and supported by suitable bearings carried by a horizontal rail 252 mounted on legs 14. Belt 248 is maintained in driving engagement with pulleys 250 by means of idler pulleys 254 and 256. Pulley 250 has a V-pulley 258 attached thereto for rotation thereby. A variable speed pulley 260 having a pair of fixed outer flanges 262 and 264 and a floating centre flange 266 is carried by shaft 267 on the end of arm 270. Arm 270 is pivotally attached to the front bar 12 of bed or table to permit variable speed pulley 260 to swing upwardly or downwardly. One side of variable speed pulley 260 is connected to V-pulley 258 by means of V-belt 268. The other side of variable speed pulley 260 is connected to V-pulley 56 of clutch mechanism 45 by V-belt 272. It will, therefore, be seen that vertical movement of variable speed pulley 260 will cause belt 268 to move floating centre flange 266 to permit belt 268 to drive said variable speed pulley at a faster rate. At the same time movement of floating centre flange 266 to the left causes belt 272 to be driven at a faster rate of speed. Conversely, lowering variable speed pulley 260 causes belt 268 to ride nearer the periphery of the variable speed pulley thus driving it at a slower rate of speed and also causes belt 272 to be driven nearer the axis of the pulley and consequently driven at a slower rate of speed. Movement of variable speed pulley 260, therefore, can be employed to

control the speed of shaft or spindle 34 and cam driving shaft 26. An idler pulley 274 carried by spring loaded arm 276 bears against belt 268 to permit the give and take of slack in said belt 268 as variable speed pulley 260 is moved upwardly or downwardly.

An adjustable mechanism for controlling variable speed pulley 260, providing an adjustable stopping arm 224 for cam 140 and for providing a differential tension control, is mounted on the lower end of front wall 33 of housing 36 in alignment with shaft 38 about which housing 36 pivots. The entire mechanism is held in place on boss 278, Fig. 5, by means of two bolts 280 and 282. Adjustable arm 224 has one of its sides contacting the face of boss 278 and is adapted to pivot around bolt 280 upon bolt 282, which passes through a slot in arm 224, being loosened. Fine adjustment of arm 224 is obtained to set the clearance between yarn guide 28 and package core 18 at the start of winding, by means of adjustment screw 284 which is threadedly carried by bent over end 286 of arm 224 and which engages a shoulder 288 formed on variable speed pulley controlling arm 290. Variable speed pulley controlling arm 290 is spaced forwardly of adjustable arm 224 by means of spacing washers carried by bolts 280 and 282. Variable speed pulley controlling arm 290 carries a bushing or sleeve 292 which is axially aligned with shaft 38 and which pivotally carries depending package sizing arm 134 and differential tension controlling arm 294. A cam carrying arm 296 is adjustably carried by the lower end of speed controlling arm 290 by means of a bolt and slot connection to said arm 290 which permits the position of said cam carrying arm 296 to be adjusted lengthwise of arm 290. Cam carrying arm 296 is provided with a cam slot 298 adapted to engage the end of shaft 267 which carries variable speed pulley 260 on arm 270. Cam slot 298 is provided with a first portion of its length 300 which is concentric with shaft 38 and with a second portion 302 which diverges from shaft 38. Arm 290 swings in a clockwise direction as viewed in Figs. 3 and 4 as spindle 34 is moved away from yarn guide 28 as the package being wound increases in diameter. It will, therefore, be seen that while shaft 267 is within the first or concentric portion 300 of cam slot 298 there will be no movement of variable speed pulley 260 and the speed of spindle 34 and traverse cam carrying shaft 26 will remain constant. The length of concentric portion 300 is such that it will leave shaft 267 at the time the peripheral speed of the package being wound is substantially equal to the maximum speed at which a strand of yarn Y can be wound. Continued clockwise motion of arm 290 causes the diverging portion 302 of cam slot 298 to lower variable speed pulley 260 to decrease the speed of spindle 34 and traverse cam shaft 26 at such a rate as to maintain constant the peripheral speed of the package being wound.

Depending sizing control arm 134 is pivotally carried by bushing or sleeve 292 and is held thereon against rotation by means of bolt 280. Differential tension controlling arm 294 is also pivotally mounted on bushing or sleeve 292 and is held against rotation thereon by means of bolts 280 and 304. The manner in which differential tension controlling arm 294 cooperates with the tension mechanism will be explained in detail hereinafter. It is sufficient to say at this point that arm 294 is provided with an arcuate slot 306 which adjustably carries one end of a tension actuating link 308.

Tension mechanism.—The present apparatus includes a novel tension applying mechanism that is capable of applying a differential tension as the yarn package increases in diameter and which is self-cleaning. Horizontal shaft 132 which drives toothed wheel 130, used in connection with the knockoff mechanism, for stopping the individual winding units upon the breakage or exhaustion of the strand of yarn being wound, is also employed to drive the self-cleaning tension disk employed in the ten-

sion mechanism. Shaft 132 is supported and suitably journaled by hanger members, to be explained in detail hereinafter, forming a part of each tension unit. Shaft 132 is driven by motor 16 through the medium of a belt 310 driven by idler pulley 254. Belt 310 in turn drives pulley 312, Fig. 1, carried by the input shaft of a speed reducing unit 314. The output shaft of speed reducing unit 314 carries a sprocket wheel which drives shaft 132 by means of sprocket chain 316 and a sprocket wheel carried by said shaft 132.

The individual tension applying units, Figs. 3, 4, 13, 14 and 15, each include a bracket 318, carried by the front horizontal bar 12 and located beneath the forward end of shaft or spindle 34 adapted to carry the package core 18. Shaft 132 is supported and suitably journaled throughout the length of the apparatus by means of a forwardly extending hanger member 319 carried by bracket 318. A rotatable tension disk 320, formed from non-magnetic material, is mounted for rotation on a stub shaft 322 carried by one end of an arm 324 pivotally connected to the lower end of bracket 318 by means of pivot pin 326. The periphery of tension disk 320 carries a rubber driving ring or tire 328 adapted to contact the periphery of a driving wheel 330 carried by shaft 132. A tension disk operating yoke 332 is mounted on shaft 132 for pivotal movement therearound. Yoke 332 is adapted to be pivoted by starting handle 80 by means of a rod 334 having its upper end engaged in an opening in said starting handle 80 and its lower end engaged in a slot 336 in yoke 332. Yoke 332 is operatively connected to arm 324 by means of rod 338 which has its upper end engaged in an opening in yoke 332 and its lower end passing through an opening in said arm 324 and adapted to lift said arm and tension disc 320 by means of compression spring 340 interposed between the end of said rod 338 and the under surface of arm 324. Downward motion of starting handle 80 moves rod 334 downwardly to bring its lower end into engagement with the lower end of slot 336 on yoke 332, whereupon continued downward movement of said starting handle rotates said yoke in a clockwise direction as viewed in Figs. 13 and 14. Clockwise rotation of yoke 332 lifts rod 338 to pivot arm 324 upwardly to bring rubber driving ring 328 carried by the periphery of tension disk 320 into engagement with the periphery of driving wheel 330 carried by shaft 132. Contact of rubber driving ring 328 with driving wheel 330 causes said driving wheel to rotate said tension disk to maintain the tension mechanism free from dirt and other foreign matter that may be carried thereto by the running strand of yarn Y. Upward movement of starting handle 80 to release clutch mechanism 45 and thus stop the operation of the winding unit pivots yoke 332 in a counterclockwise direction as viewed in Figs. 13 and 14 to move tension disk 320 away from driving wheel 330 to stop the rotation of said tension disk.

A tension plate 342 is held closely adjacent to one surface of tension disk 320 by means of arm 344, Fig. 15. Tension plate 342 is held loosely by arm 344 by means of a pin 346 attached to the back of said tension plate 342 and approximately on its centre line to permit said plate to oscillate on said arm and to be drawn into contact with the adjacent face of tension disk 320 by magnetic means to be described hereinafter. An oscillation limiting member 348 having a pair of spaced outwardly turned abutments 350 and 352 formed on its upper edge is attached to the back surface of tension plate 342 beneath pin 346 and is so located on said tension plate 342 that the abutments 350 and 352 can contact the lower edge of arm 344 to limit the amount that said plate can oscillate. Tension plate 342 is located between the axis of tension disk 320 and its periphery so that rotation of said tension disk causes the entire surface thereof covered by tension plate 342 to be constantly changing. The strand of yarn Y being wound passes between tension disk

320 and tension plate 342 to have applied thereto a predetermined tension by means of a magnet to be described hereinafter. A plurality of radial grooves 354 are formed in the face of tension disk 320 which contacts tension plate 342 to collect dirt and other foreign matter drawn between tension plate 342 and tension disk 320 by the running strand of yarn Y and to carry such foreign matter out from between said two members.

A fixed shaft 356 extends forwardly from hanger member 319 and pivotally carries U-shaped magnet holder 358. A permanent magnet 360 is carried by magnet holder 358 and is located by said holder opposite the upper portion of tension plate 342 and on the opposite side of tension disk 320 from said tension plate. Inasmuch as tension disk 320 is formed from a nonmagnetic material the lines of flux from magnet 360 pass through said disk and draw tension plate 342 against the surface of disk 320 and the strand of yarn therebetween. It will be seen that the force with which tension plate 342 is held against tension disk 320 and the strand of yarn Y can be varied to increase said force by moving magnet 360 closer to tension disk 320 and conversely the force can be decreased by moving magnet 360 away from said disk. Means are provided for readily adjusting the location of magnet 360 with respect to tension plate 320 and also for moving said magnet away from said disk as the package being wound increases in diameter to thereby cause the strand of yarn Y to be wound under a decreasing tension as it increases in diameter.

As explained above, tension actuating link 308 is adjustably connected to and is moved by differential tension controlling arm 294. The other end of link 308 is pivotally connected to the end of lever 362, Figs. 3 and 4, which is fast upon one end of shaft 364, Figs. 13 and 14. Shaft 364 is suitably journaled in a pair of lugs extending from the side of hanger 319. The other end of shaft 364 has a lever 366 fixedly attached thereto and which has a cam slot 368 formed therein. Magnet adjusting plate 370 is pivotally carried adjacent its upper end by shaft 356 and is adjustably secured to one side of U-shaped magnet holder 358 by means of a bolt and nut 372 which passes through a hole in the side of magnet holder 358 and an arcuate slot in magnet adjusting plate 370. It will, therefore, be seen that the initial position of magnet 360 with respect to tension disk 320 can be established by loosening bolt and nut 372, locating said magnet in its desired starting position and tightening said bolt and nut. A cam following roller 374 carried by magnet adjusting plate 370 engages cam slot 368 in lever 366 so that movement of said lever 366 will pivot said adjusting plate 370, U-shaped magnet holder 358 and magnet 360. As the winding cycle progresses and differential tension controlling arm 294 swings in a clockwise direction link 308 is moved from right to left as viewed in Figs. 3 and 4. This movement of link 308 rotates lever 362 in a counter-clockwise direction and lever 362 acting through shaft 364 rotates lever 366 in the same direction. The counter-clockwise rotation of lever 366 acting through cam slot 368 and cam follower 374 pivots magnet adjusting plate 370 and with it magnet holder 358 and magnet 360 away from tension disk 320 to decrease the tension applied to the running strand of yarn Y as the package increases in diameter. The rate at which magnet 360 is moved away from tension disk 320 and the total distance which it is moved during a winding cycle can be adjusted by moving the location of the end of link 308 in arcuate slot 306.

The tension mechanism is provided with yarn guiding means to facilitate threading the apparatus, and to guide the strand of yarn Y as the package is being wound so that it passes between tension disk 320 and tension plate 342. A forwardly extending yarn engaging bar 376 is carried by the upper edge of hanger member 319 with one of its edges in substantially the same plane as the yarn

contacting surface of tension disk 320. A yarn guiding slot is formed in the bottom leg of an L-shaped plate 380 which extends beneath tension disk 320 and tension plate 342. L-shaped plate 380 is supported by an angular member 382 having one of its ends attached to the bottom of bracket 318 and its other end attached to the end of shaft 356. A curved yarn threading guide 384 is attached to the angular member 382 adjacent shaft 356 and is so shaped that it covers the forward edge of tension disk 320 to guide the strand of yarn Y between said disk 320 and tension plate 342 when the tension is being threaded. A curved rod 386 also is positioned in front of the forward edge of tension disk 320 by having its upper end attached to forwardly extending yarn engaging bar 376 and its lower end attached to the bottom leg 378 of the L-shaped plate 380. In threading the tension mechanism the strand of yarn is moved rearwardly on the right hand side of curved rod 386, as viewed in Figs. 3 and 4, and brought into engagement with curved yarn threading guide 384 which guides it between tension disk 320 and tension plate 342. The strand of yarn beneath the tension is then moved rearwardly to cause the lower portion of curved rod 386 to guide the strand of yarn into the yarn guiding slot formed in the bottom leg 378 of L-shaped plate 380.

Method of operation.—The apparatus of the present invention is threaded preparatory to starting winding cycle by placing a supply of yarn on shelf 15, passing the strand of yarn Y between tension disk 320 and tension plate 342 of the tension assembly and between forwardly extending yarn engaging bars 376 of the tension assembly and 124 of the stop mechanism and wrapping the end of the yarn around expanding mandrel 229. An empty package core or yarn holder 18 is then placed on mandrel 229 to clamp the end of the yarn therebetween and clamping lever 230 is pulled forwardly to expand said mandrel to clamp core 18 thereon. The forward swinging movement of clamping lever 230 acting through link 236 and rod operating lever 238 draws rod 208 back into hollow shaft 190 causing its cam surface 210 to move pawl releasing link 202 outwardly. This movement of link 202 causes finger 212 thereon to release pawl 198 from the teeth on ratchet wheel 194 whereupon helical spring 214 rotates spiral cam 140 back to its starting position. Release of lever 230 permits spring 244 to move rod 208 out of hollow shaft 190 a sufficient distance to release cam surface 210 from pawl releasing link 202 to permit pawl 198 to again engage the teeth on ratchet wheel 194.

Starting handle 80 is then depressed straightening the toggle linkage formed by upstanding finger 90 and link 92 to move roller 94 towards the traverse mechanism and thereby permit package core 18 to move closely adjacent to yarn guide 28 into its winding position. Lowering starting handle 80 also brings latch shoulder 104 on latch member 98 over keeper member 106 carried by starting handle 80 to latch said handle in its lowered or operating position and to maintain roller 94 at its winding position. Lowering starting handle 80 also swings L-shaped actuating arm 84 in a direction to release the brake 76 from outer flange 66 of the clutch member 45. Releasing brake member 76 permits spring 74 of the clutch mechanism to move clutch plate 60 into engagement with the clutch facing 58 on V-pulley 56. Engagement of the clutch mechanism causes pulleys 42 and 44 to be rotated by motor 16 by means of belt 248 which drives pulleys 250 and 258 and belt 268 which drives variable speed pulley 260. V-pulley 56 is driven by variable speed pulley 260 by means of belt 272. Rotation of pulley 42 drives belt 46 to rotate pulley 40 and shaft or spindle 34 and package core 18 to cause the strand of yarn Y to be wound on said package core. Rotation of pulley 44, by means of belt 52, double pulley 48, belt 32 and pulley 30, rotates cam shaft 26 to rotate the cam carried thereby and to reciprocate yarn guide 28 longitudinally of package core 18 to traverse strand of yarn Y thereacross.

Rotation of spindle 34 to wind strand of yarn Y on

package core 18 is transmitted to spiral cam 140 to rotate said cam at such a rate that it will, by reason of its periphery being in contact with roller 94, move said spindle 34 and package core 18 and the yarn wound thereon away from yarn guide 28 at substantially the same rate as the radius of the package being wound increases. The rotation of spindle 34 is transmitted to cam 140 through a speed reducing mechanism comprising worm gear 142 carried by said spindle and driving worm wheel 144. Worm wheel 144 drives crank disk 148 which reciprocates ratchet pawl 156 to rotate ratchet wheel 162. Ratchet wheel 162 drives pinion gear 164 which acting through gears 168, 170, 172 and 174 drives change gear 182. Change gear 182 drives worm gear 186 which is meshed with and drives worm wheel 188 carried by hollow shaft 190. Spiral cam 140 is carried by hollow shaft 190 for rotation thereby.

Upon the breakage or exhaustion of the strand of yarn Y breakage lever 110 is permitted to pivot in a clockwise direction to bring its abutment 128 in contact with the toothed surface of toothed wheel 130. Abutment 128 is engaged by one of the teeth on toothed wheel 130 which lifts lever 110 to pivot latch member 98 to disengage its latch shoulder 104 from keeper member 106 on starting handle 80 thus permitting spring 96 to lift said starting handle. When starting handle 80 is lifted by its spring 96 L-shaped actuating arm 84 moves brake 76 against flange 66 of the clutch mechanism 45 to disengage clutch plate 60 from the clutch facing 58 of pulley 56 to thereby stop the rotation of spindle 34 and the reciprocation of yarn guide 28. The upward movement of starting handle 80 also breaks the toggle formed by upstanding finger 90 and link 92 to move roller 94 in a direction to cause it to move spindle 34 and the package of yarn carried thereby away from yarn guide 28.

As the package being wound increases in diameter the movement of spindle 34, and the package carried thereby, away from yarn guide 28 causes housing 36 to pivot around shaft 38. This swinging or pivoting movement of housing 36 swings variable speed pulley controlling arm 290 and depending arm 134 carried thereby to cause lug 136 formed on the end of said arm 134 to approach the lowermost end 138 of latch member 98 as the package grows. When the package being wound attains its predetermined desired size lug 136 contacts the lowermost end 138 of latch member 98 to rotate said latch member to release its latch shoulder 104 from keeper member 106 permitting starting handle 80 to be lifted by spring 96 to stop the operation of the winding unit and to move the fully wound package away from yarn guide 28 to permit said package to be removed from the spindle without danger of damaging the yarn by contact with said yarn guide.

The swinging or pivoting of variable speed pulley controlling arm 290 moves cam slot 298 of cam carrying arm 296 across the end of shaft 267 whereby said cam slot during the first portion of its motion holds variable speed pulley 260 at a fixed location and subsequently lowers said pulley at a predetermined rate to cause said variable speed pulley during the remainder of the winding cycle to reduce the speed of shaft or spindle 34 and cam shaft 26 to maintain the speed at which the strand of yarn Y is wound on the package substantially constant.

Lowering starting handle 80 moves rod 334 connected thereto downwardly to lift tension disk 320 to bring its periphery into contact with driving wheel 330 carried by shaft 132 to thereby rotate said tension disk to permit the radial grooves 354 formed in said disk to collect dirt and other foreign matter carried into the tension by the running strand of yarn and remove it therefrom before it has an opportunity to build up to an extent sufficient to affect the functioning of the tension.

The swinging or pivoting of variable speed pulley controlling arm 290 by the growth of the package also swings differential tension controlling arm 294 to move tension

actuating link 308 to pivot lever 366 carrying cam slot 368 by means of lever 362 connected to link 308 and shaft 364 which carries lever 366. Movement of cam slot 368 swings permanent magnet 360 away from the back of tension disk 320 by means of magnet adjusting plate 370 which engages said cam slot and is connected to U-shaped magnet holder 358.

Since certain changes may be made in the above apparatus without departing from the scope of the invention herein involved, it is intended that all matter contained in the above description or shown in the accompanying drawings shall be interpreted as illustrative and not in a limiting sense.

What is claimed is:

15. In a winding machine the combination comprising a winding spindle adapted to hold a package core, a yarn guide for reciprocating a strand of yarn longitudinally of said spindle, a source of power for rotating said spindle and operating said yarn guide, means for selectively connecting said source of power to and disconnecting it from said spindle and yarn guide, a manually operable lever movable to operate said connecting and disconnecting means, means urging said lever in the direction to disconnect said source of power from said spindle and yarn guide, latch means for holding said lever in the position wherein said source of power is connected to said spindle and yarn guide, a link associated with said lever and movable thereby for separating said spindle and yarn guide as said lever moves in the direction to disconnect said source of power, and means operative upon the breakage or exhaustion of a strand of yarn being wound for releasing said latch.
20. In a winding machine the combination comprising a winding spindle adapted to hold a package core, a yarn guide for reciprocating a strand of yarn longitudinally of said spindle, a source of power for rotating said spindle and operating said yarn guide, means for selectively connecting said source of power to and disconnecting it from said spindle and yarn guide, a manually operable lever movable to operate said connecting and disconnecting means, means urging said lever in the direction to disconnect said source of power from said spindle and yarn guide, latch means for holding said lever in the position wherein said source of power is connected to said spindle and yarn guide, a link associated with said lever and movable thereby for separating said spindle and yarn guide as said lever moves in the direction to disconnect said source of power, and means operative upon the breakage or exhaustion of a strand of yarn being wound for releasing said latch.
25. In a winding machine the combination comprising a winding spindle adapted to hold a package core, a yarn guide for reciprocating a strand of yarn longitudinally of said spindle, a source of power for rotating said spindle and operating said yarn guide, means for selectively connecting said source of power to and disconnecting it from said spindle and yarn guide, a manually operable lever movable to operate said connecting and disconnecting means, means urging said lever in the direction to disconnect said source of power from said spindle and yarn guide, latch means for holding said lever in the position wherein said source of power is connected to said spindle and yarn guide, a link associated with said lever and movable thereby for separating said spindle and yarn guide as said lever moves in the direction to disconnect said source of power, and means operative upon the breakage or exhaustion of a strand of yarn being wound for releasing said latch.
30. In a winding machine the combination comprising a winding spindle adapted to hold a package core, a yarn guide for reciprocating a strand of yarn longitudinally of said spindle, a source of power for rotating said spindle and operating said yarn guide, means for selectively connecting said source of power to and disconnecting it from said spindle and yarn guide, a manually operable lever movable to operate said connecting and disconnecting means, means urging said lever in the direction to disconnect said source of power from said spindle and yarn guide, latch means for holding said lever in the position wherein said source of power is connected to said spindle and yarn guide, a link associated with said lever and movable thereby for separating said spindle and yarn guide as said lever moves in the direction to disconnect said source of power, and means operative upon the breakage or exhaustion of a strand of yarn being wound for releasing said latch.
35. In a winding machine the combination comprising a winding spindle adapted to hold a package core, a yarn guide for reciprocating a strand of yarn longitudinally of said spindle, a source of power for rotating said spindle and operating said yarn guide, means for selectively connecting said source of power to and disconnecting it from said spindle and yarn guide, a manually operable lever movable to operate said connecting and disconnecting means, means urging said lever in the direction to disconnect said source of power from said spindle and yarn guide, latch means for holding said lever in the position wherein said source of power is connected to said spindle and yarn guide, a link associated with said lever and movable thereby for separating said spindle and yarn guide as said lever moves in the direction to disconnect said source of power, and means operative upon the package being wound attaining a predetermined size for releasing said latch.
40. In a winding machine the combination comprising a winding spindle adapted to hold a package core, a yarn guide for reciprocating a strand of yarn longitudinally of said spindle, a source of power for rotating said spindle and operating said yarn guide, means for selectively connecting said source of power to and disconnecting it from said spindle and yarn guide, a manually operable lever movable to operate said connecting and disconnecting means, means urging said lever in the direction to disconnect said source of power from said spindle and yarn guide, latch means for holding said lever in the position wherein said source of power is connected to said spindle and yarn guide, a link associated with said lever and movable thereby for separating said spindle and yarn guide as said lever moves in the direction to disconnect said source of power, and means operative upon the package being wound attaining a predetermined size for releasing said latch.
45. In a winding machine the combination comprising a winding spindle adapted to hold a package core, a yarn guide for reciprocating a strand of yarn longitudinally of said spindle, a source of power for rotating said spindle and operating said yarn guide, means for selectively connecting said source of power to and disconnecting it from said spindle and yarn guide, a manually operable lever movable to operate said connecting and disconnecting means, means urging said lever in the direction to disconnect said source of power from said spindle and yarn guide, latch means for holding said lever in the position wherein said source of power is connected to said spindle and yarn guide, a link associated with said lever and movable thereby for separating said spindle and yarn guide as said lever moves in the direction to disconnect said source of power, and means operative upon the package being wound attaining a predetermined size for releasing said latch.
50. In a winding machine the combination comprising a winding spindle adapted to hold a package core, a yarn guide for reciprocating a strand of yarn longitudinally of said spindle, a source of power for rotating said spindle and operating said yarn guide, means for selectively connecting said source of power to and disconnecting it from said spindle and yarn guide, a manually operable lever movable to operate said connecting and disconnecting means, means urging said lever in the direction to disconnect said source of power from said spindle and yarn guide, latch means for holding said lever in its clutch engaging position, a toggle having one of its ends connected to said lever whereby movement of said lever causes said toggle to bend or straighten, an abutment carried by said toggle and movable therewith for separating said spindle and yarn guide when said lever moves in the direction to disconnect said source of power, and means for releasing said latch.
55. In a winding machine the combination comprising a winding spindle adapted to hold a package core, a yarn guide for reciprocating a strand of yarn longitudinally of said spindle, a source of power for rotating said spindle and operating said yarn guide, means for selectively connecting said source of power to and disconnecting it from said spindle and yarn guide, a manually operable lever movable to operate said connecting and disconnecting means, means urging said lever in the direction to disconnect said source of power from said spindle and yarn guide, latch means for holding said lever in its clutch engaging position, a toggle having one of its ends connected to said lever whereby movement of said lever causes said toggle to bend or straighten, an abutment carried by said toggle and movable therewith for separating said spindle and yarn guide when said lever moves in the direction to disconnect said source of power, and means for releasing said latch.
60. In a winding machine the combination comprising a winding spindle adapted to hold a package core, a yarn guide for reciprocating a strand of yarn longitudinally of said spindle, a source of power for rotating said spindle and operating said yarn guide, means for selectively connecting said source of power to and disconnecting it from said spindle and yarn guide, a manually operable lever movable to operate said connecting and disconnecting means, means urging said lever in the direction to disconnect said source of power from said spindle and yarn guide, latch means for holding said lever in its clutch engaging position, a toggle having one of its ends connected to said lever whereby movement of said lever causes said toggle to bend or straighten, an abutment carried by said toggle and movable therewith for separating said spindle and yarn guide when said lever moves in the direction to disconnect said source of power, and means for releasing said latch.
65. In a winding machine the combination comprising a winding spindle adapted to hold a package core, a yarn guide for reciprocating a strand of yarn longitudinally of said spindle, a source of power for rotating said spindle and operating said yarn guide, means for selectively connecting said source of power to and disconnecting it from said spindle and yarn guide, a manually operable lever movable to operate said connecting and disconnecting means, means urging said lever in the direction to disconnect said source of power from said spindle and yarn guide, latch means for holding said lever in its clutch engaging position, a toggle having one of its ends connected to said lever whereby movement of said lever causes said toggle to bend or straighten, an abutment carried by said toggle and movable therewith for separating said spindle and yarn guide when said lever moves in the direction to disconnect said source of power, and means for releasing said latch.
70. In a winding machine the combination comprising a winding spindle adapted to hold a package core, a yarn guide for reciprocating a strand of yarn longitudinally of said spindle, a source of power for rotating said spindle and operating said yarn guide, a clutch for selectively connecting said source of power to and disconnecting it from said spindle and yarn guide, a manually operable

lever movable to engage and disengage said clutch, means urging said lever in the direction to disengage said clutch, latch means for holding said lever in its clutch engaging position, a link associated with said lever and movable thereby for separating said spindle and yarn guide as said lever moves from its clutch engaging position to its clutch disengaging position, and means operative upon the breakage or exhaustion of a strand of yarn being wound for releasing said latch.

5. In a winding machine the combination comprising a winding spindle adapted to hold a package core, a yarn guide for reciprocating a strand of yarn longitudinally of said spindle, a source of power for rotating said spindle and operating said yarn guide, a clutch for selectively connecting said source of power to and disconnecting it from said spindle and yarn guide, a manually operable lever movable to engage and disengage said clutch, means urging said lever in the direction to disengage said clutch, latch means for holding said lever in its clutch engaging position, a link associated with said lever and movable thereby for separating said spindle and yarn guide as said lever moves from its clutch engaging position to its clutch disengaging position, and means operative upon the package being wound attaining a predetermined size for releasing said latch.

6. In a winding machine the combination comprising a winding spindle adapted to hold a package core, a yarn guide for reciprocating a strand of yarn longitudinally of said spindle, a source of power for rotating said spindle and operating said yarn guide, a clutch for selectively connecting said source of power to and disconnecting it from said spindle and yarn guide, a manually operable lever movable to engage and disengage said clutch, means urging said lever in the direction to disengage said clutch, latch means for holding said lever in its clutch engaging position, a toggle having one of its ends connected to said lever whereby movement of said lever causes said toggle to bend or straighten, an abutment carried by said toggle and movable therewith for separating said spindle and yarn guide when said lever moves in the direction to disengage said clutch, and means for releasing said latch.

7. In a winding machine the combination comprising a rotatable winding spindle, holding means carried by said spindle for selectively clamping a yarn receiving core thereon and releasing said core therefrom, manually operable means movable in a first direction to bring said holding means into its core clamping position and movable in a second direction to bring said holding means into its core releasing position, a yarn guide adapted to traverse a strand of yarn longitudinally of said core to wind a package of yarn thereon, mounting means supporting said spindle for movement towards and away from said yarn guide, a source of power for rotating said spindle to wind a strand of yarn on a core carried thereby, means carried by said spindle mounting means and operated by said source of power to positively move said spindle away from said yarn guide as the package being wound increases in diameter, and a link connecting said manually operable means and said last mentioned means whereby movement of said operable means in said first direction disengages said last mentioned means from said source of power to thereby permit said spindle to move towards said yarn guide.

8. In a winding machine the combination comprising a rotatable winding spindle, holding means carried by said spindle for selectively clamping a yarn receiving core thereon and releasing said core therefrom, manually operable means movable in a first direction to bring said holding means into its core clamping position and movable in a second direction to bring said holding means into its core releasing position, a yarn guide adapted to traverse a strand of yarn longitudinally of said core to wind a package of yarn thereon, mounting means supporting said spindle for movement towards and away from said yarn guide, a source of

power for rotating said spindle to wind a strand of yarn on a core carried thereby, a cam carried by said spindle mounting means for operation by said source of power to positively move said spindle away from said yarn guide as the package being wound increases in diameter, and a link connected to said manually operable means and operatively associated with said cam whereby movement of said operable means in said first direction disengages said cam from said source of power to thereby permit said spindle to move towards said yarn guide.

9. In a winding machine the combination comprising a winding spindle adapted to hold a package core, a yarn guide for reciprocating a strand of yarn longitudinally of said spindle, a source of power for rotating said spindle and operating said yarn guide, means for selectively connecting said source of power to and disconnecting it from said spindle and yarn guide, a lever movable to operate said connecting and disconnecting means, means urging said lever in the direction to disconnect said source of power from said spindle and yarn guide, latch means for holding said lever in the position wherein said source of power is connected to said spindle and yarn guide, a stop member carried by said lever for movement therewith, means actuated by said source of power and engageable with said stop member to positively separate said spindle and yarn guide as the package being wound increases in diameter, and means operative upon the breakage or exhaustion of a strand of yarn being wound for releasing said latch whereby movement of said lever will space the periphery of the package being wound from said yarn guide.

10. In a winding machine the combination comprising a winding spindle adapted to hold a package core, a yarn guide for reciprocating a strand of yarn longitudinally of said spindle, a source of power for rotating said spindle and operating said yarn guide, means for selectively connecting said source of power to and disconnecting it from said spindle and yarn guide, a lever movable to operate said connecting and disconnecting means, means urging said lever in the direction to disconnect said source of power from said spindle and yarn guide, latch means for holding said lever in the position wherein said source of power is connected to said spindle and yarn guide, a stop member carried by said lever for movement therewith, a cam actuated by said source of power and engageable with said stop member to positively separate said spindle and yarn guide as the package being wound increases in diameter, and means operative upon the breakage or exhaustion of a strand of yarn being wound for releasing said latch whereby movement of said lever will space the periphery of the package being wound from said yarn guide.

11. In a winding machine the combination comprising a winding spindle, holding means carried by said spindle to selectively clamp a yarn receiving core thereon and release it therefrom, manually operable means for moving said holding means from core clamping position to core releasing position and from core releasing to core clamping position, a reciprocating yarn guide adapted to traverse a strand of yarn longitudinally of said core to wind a package of yarn thereon, a cam, a stop member positioned to be engaged by said cam, a driving connection between said spindle and said cam whereby rotation of said spindle moves said cam from a starting position wherein said spindle is adjacent said yarn guide to progressively separate said spindle and yarn guide as the winding cycle progresses, and means actuated by said manually operable means for disengaging said driving connection to permit said cam to return to its starting position.

12. In a winding machine the combination comprising a winding spindle, holding means carried by said spindle to selectively clamp a yarn receiving core thereon and release it therefrom, manually operable means

for moving said holding means from core clamping position to core releasing position and from core releasing to core clamping position, a reciprocating yarn guide adapted to traverse a strand of yarn longitudinally of said core to wind a package of yarn thereon, a cam, a stop member positioned to be engaged by said cam, a driving connection comprising a ratchet and pawl between said spindle and said cam whereby rotation of said spindle moves said cam from a starting position wherein said spindle is adjacent said yarn guide to progressively separate said spindle and yarn guide as the winding cycle progresses, and means actuated by said manually operated means for moving said pawl out of engagement with said ratchet to permit said cam to return to its starting position.

13. In a winding machine the combination comprising a winding spindle, holding means carried by said spindle adapted to receive a yarn receiving core thereon, a reciprocating yarn guide adapted to traverse a strand of yarn longitudinally of said core to wind a package of 20 yarn thereon, a substantially constant speed source of power for rotating said spindle and reciprocating said yarn guide, a variable speed mechanism interposed between said source of power and said spindle and yarn guide, means driven by said source of power to positively separate said spindle and yarn guide as the package being wound increases in diameter, and a cam moved by the separation of said spindle and said yarn guide for regulating said variable speed mechanism to reduce the speed at which said source of power rotates said spindle and 25 reciprocates said yarn guide.

14. In a winding machine the combination comprising a winding spindle, holding means carried by said spindle adapted to receive a yarn receiving core thereon, a 30

reciprocating yarn guide adapted to traverse a strand of yarn longitudinally of said core to wind a package of yarn thereon, a substantially constant speed source of power for rotating said spindle and reciprocating said 5 yarn guide, a variable speed mechanism interposed between said source of power and said spindle and yarn guide, means driven by said source of power to positively separate said spindle and yarn guide as the package being wound increases in diameter, and a cam moved by the separation of said spindle and said yarn guide for regulating said variable speed mechanism to reduce the speed at which said source of power rotates said spindle and reciprocates said yarn guide, the contour of said cam being such that the speed at which said spindle is rotated and 10 said yarn guide reciprocated is varied only during a portion of the separation thereof.
